[57] CLAIM

The ornamental design for a combined pill reminder calendar and message board, as shown and described.

DESCRIPTION

FIG. 1 is a front elevational view of the combined pill reminder calendar and message board showing my new design;

FIG. 2 is a rear elevational view thereof;

FIG. 3 is an enlarged left side elevational view thereof;

FIG. 4 is an enlarged right side elevational view thereof;

FIG. 5 is an enlarged top plan view thereof;

FIG. 6 is an enlarged bottom plan view thereof; and,

FIG. 7 is an isometric view thereof.

The broken lines shown in FIGS. 1 and 7 are for illustrative purposes only forming no part of the claimed design.
